UNITED STATES PATENT OFFICE.

CHARLES W. T. DAVIES, OF NEW YORK, N. Y.

FOLDING CUFF.

1,141,942.

Specification of Letters Patent.

Patented June 8, 1915.

Application filed July 26, 1913. Serial No. 781,310.

To all whom it may concern:

Be it known that I, CHARLES W. T. DAVIES, a subject of the King of Great Britain, residing at New York, county of New York, and State of New York, have invented certain new and useful Improvements in Folding Cuffs, of which the following is a specification.

This invention relates to folding cuffs. The ordinary folding cuff having buttonholes in its respective folds is frequently laundried with the folds out of symmetrical relation, or, if not folded in laundrying, entails care on the part of the user to bring the folds in symmetrical relationship with the buttonholes or properly arranged for the insertion of the cuff link or stud.

My object is to provide means on folding cuffs, preferably those of soft fabric not intended for starching, whereby symmetrical folding in respect to the upper edge of the cuff and the relative disposition of the buttonholes in the folds thereof, is rendered easy, whether such folding is done during laundrying or afterward by the wearer.

The object of the invention is accomplished by connecting the edges of the folds of the cuff, so that they may be held in exact mutual adjustment whichever one be outermost in relation to the sleeve on which the cuff is attached, such connecting means permitting the cuff to be freely folded along the same natural and proper upper edge either during laundrying or by the wearer, and insuring a constant symmetrical relation of all the parts of the cuff not only with regard to its upper edge but also in regard to its buttonholes, whereby the latter are necessarily brought opposite each other, in such position as may be desired for convenient and easy insertion of the cuff link or stud. One or more connecting means between the outer edges of the folds of the cuff may be provided and such connecting means, preferably of exceedingly short length located at any preferred point along said edges, but preferably, opposite or adjacent the buttonholes so as to leave the parts open between each of such folded

edges and the connector or "bridge-piece" for the insertion of the finger and thumb over and under said connector, thus facilitating the manipulation of the cuff links during their passage from one to the other of the two respective buttonholes. The folds of the cuff may have the ordinary button-

holes which extend longitudinally of the cuff, or, intersecting buttonholes on the respective superposed folds may be provided, such as are set forth in my application, but 60 buttonholes for wearing apparel, Serial No. 749,832, filed February 21, 1913. I do not limit myself to the use of the present invention in connection with any particular kind or arrangement of buttonhole, nor to 65 any particular relation of the present connecting means and the buttonholes of the cuff.

Certain embodiments of the invention are set forth fully hereinafter and are shown in 70 the accompanying drawings, in which—

Figure 1 is a perspective of a folding soft cuff provided with the present improvements, the upper part of which is folded over on the outside of the shirt sleeve; Fig. 75 2 shows the outer fold of Fig. 1 in the act of being reversed to lie on the inner side of the shirt sleeve; Fig. 3 shows the outer fold of Figs. 1 and 2 after it has been reversed to the inner side of the shirt sleeve; Fig. 4, an 80 edge view showing one manner of carrying out the invention; Fig. 5, a similar view illustrating another form; and Fig. 6, a similar view showing how the folds of the cuff and the connecting member at the edges 85 thereof may be integral.

The shirt sleeve to which the cuff is attached is shown at 1, the folding soft cuff being composed of the parts 2 and 3 which are designed to fold along or substantially 90 at a common upper edge 4, whether the fold 3 be outermost, as in Fig. 1, or innermost, as in Fig. 3, in relation to the sleeve 1. I have shown my improved crossed or intersecting buttonholes 5, 6, in the respective folds of 95 the cuff, such buttonholes constituting the subject-matter of a copending application, Serial No. 749,832, filed February 21, 1913, but I do not claim these buttonholes herein, nor do I limit the present invention to the 100 use in connection with such buttonholes, as it is just as well adapted for use in connection with the usual buttonholes which extend longitudinally of the cuff.

The edges 7 and 8 of the cuff are connected by any suitable connecting device, or means, 105 9, the inner surfaces of the folds 2, 3, being entirely detached from each other and connected only as shown in drawings. The connector 9 may be suitable stitching or over-stitching, as shown in Figs. 1, 2, 3 and 5, or a tape 10, Fig. 4, or a member 11, Fig.

6, which is integral with the folds 2 and 3. The connector may be attached or sewed to the extreme outer edge of the folds 2, 3, or just inwardly from said edge, or have its end 5 parts entered between the plies of the folds 2, 3, the last construction being shown in Fig. 4. If desired, two or more of the connectors may be provided, as shown in Fig. 5. However made and connected with the folds 10 2, 3, I do not limit myself to any exact position of the connector in relation to the buttonholes, but they are preferably arranged substantially opposite the buttonholes as this is an advantageous position because as above mentioned it leaves suitable open parts both above and below the connector.

When the cuff is being laundered, the freedom of the folds 2, 3, from each other permits their entire surfaces to be readily 20 ironed inside, as well as outside, but the connectors 9 insure the symmetrical arrangement of the folds 2, 3, regardless of whether the free fold 3 is outermost, as shown in Fig. 1, or innermost, as shown in Fig. 3, and, if 25 the wearer prefers to change the position of

the free fold 3 while wearing the shirt, he can readily do so with the assurance that when said fold has been reversed, which operation is shown at its beginning in Fig. 2, the folds 2, 3, will still be symmetrically 30 adjusted toward one another both as regards the edge 4 and the disposition of the buttonholes 5, 6.

Having thus described my invention, what I claim as new and desire to secure by Let- 35 ters Patent, is:—

A folding cuff having inner and outer folds provided with buttonholes adapted to receive cuff buttons and connected at their vertical side edges by one or more intermediate connectors independent of the cuff buttons, the remaining portions of the folds being disconnected.

In testimony whereof, I hereunto affix my signature in presence of two witnesses.

CHARLES W. T. DAVIES.
